UNITED STATES PATENT OFFICE.

PETER S. MEISTER, OF CAMARGO, ILLINOIS.

CLOTHES-HANGER.

1,168,531.

Specification of Letters Patent. Patented Jan. 18, 1916.

Application filed February 13, 1914. Serial No. 818,439.

To all whom it may concern:

Be it known that I, PETER S. MEISTER, a citizen of the United States, residing at 5 Camargo, in the county of Douglas and State of Illinois, have invented certain new and useful Improvements in Clothes-Hangers, of which the following is a specification.

The invention relates to clothes hangers and has for its object to provide an improved collapsible device adapted for securement to the sides of walls and other approximately vertical surfaces, and having a plurality of arms radially arranged and adapted to be placed in operative position or collapsed to an inoperative position at will in order to occupy a minimum amount of space when not in use.

It is a further object of the invention to provide in a device of the described character a supporting device or bracket of improved construction for collapsibly supporting a plurality of radial arms.

Other objects of the invention will appear from the following description of the preferred embodiment of my invention and as shown in the drawings forming a part of the specification and finally pointed out more specifically in the claims.

In the said drawings Figure 1 is a top plan view of the device in its extended form attached to a wall, the latter being shown in section. Fig. 2 is a vertical section on line 2—2 of Fig. 1. Fig. 3 is a detail section on line 3—3 of Fig. 1. Fig. 4 is a plan view of a cut and unfolded blank from which the supporting bracket of the device is formed.

The device consists essentially of a wall bracket and a plurality of collapsible radiating arms supported thereby, the said arms being of any desired and convenient length and being adapted to support various articles such as clothing and the like in the well known manner.

The bracket or support for the arms is preferably formed of sheet metal and in Fig. 4 is shown a blank from which the same may be formed by bending along the dotted lines until it assumes the form shown in Figs. 1 and 2. This blank consists of a body portion indicated by the reference character 10 provided with a plurality of openings indicated at 11 and adapted to receive suitable screws or bolts as indicated at 12, Fig. 2, for the securement of the supporting bracket to the vertical surface of a wall or

any other desired supporting means, the wall portion being indicated by the reference character 13 in Figs. 1 and 2.

Integrally with the portion 10 a portion 60 is formed of a semi-circumference, as indicated by the reference character 14, and around its periphery it is provided with a plurality of openings 15 which are arranged some distance from the outer periphery 65 around the circumference and are adapted to receive the bent ends of the radially arranged rods for supporting clothes or other objects in the following manner. Between the openings 15 and the outer periphery of 70 the supporting member 14 the material is depressed or troughed, as shown at 14^a, which affords a means for steadyng the radial rods 16, of which there may be any desired number corresponding to the openings 15 and the trough portions 14^a leading therefrom. The form of the collapsible radial rod 16 may best be seen by an inspection of Fig. 2, from which it will be seen that the extremity adapted to coöperate 75 with the bracket is bent into an approximately U shape, the corners being given preferably a right-angular bend and having a portion, as indicated as 10^a, extending at right angles to the main body portion, and a 80 portion 16^b of about the same length as the angular portion 16^a extending at right angles to the last named portion and parallel with the main body portion 16.

In order to strengthen the bracket, and particularly the portion 14 which supports the radial arms 16, the portion 10 is preferably constructed beyond the vertical lines of fold 10^a with wing or brace portions 10^b having tongues extending vertically at 10^c 85 and being adapted to pass through suitable coöperating openings 14^b in the semi-circumferential plate 14 when this is bent along the line of fold as indicated at 10^d. In order to enable the wings 10^b to fold along 90 the lines of fold 10^c the material therein is preferably severed from the material of the semi-circumferential portion 13 inwardly to the lines of fold 10^a, as indicated at 10^d, and this construction will permit the members 10^b to be folded preferably upon the curved lines as indicated in Fig. 1 until the projections 10^c may be passed through the openings 14^b in the semi-circumferential plate 14, when they may be secured therein by upsetting or riveting on the top side of the plate 14. This construction produces a 105 110

bracket that is very cheap to manufacture and is at the same time very strong and efficient.

It is an important feature of a device of this character that it shall be capable of having its supporting arms radially extended for use and when not in use may permit the arms to be folded out of the way. In my improved device this is accomplished by manipulating the supporting arms 16 heretofore described, in the following manner. The arms are placed in a position where they may hang from the semi-circumferential plate 14 of the bracket in the manner best shown in Fig. 2, with a portion 16^b extending downwardly through the openings 15 and with the portions 16^a resting in each of the grooves or depressions 14^a, which will allow each of the arms 16 to be freely suspended and if the members 16^b are made of sufficient length there will be little or no tendency for these members to become disconnected from the supporting bracket even when hanging loosely in the collapsed position. When it is desired to expand the arms to their radial and operative position this may be accomplished by the operator grasping the portion 16 and bringing it to the horizontal position, as shown in Fig. 2, the arms may each be pushed inwardly toward the center of the semi-circumferential plate 14, which will cause the inner portions of the members 16, to slide beneath the body portion of the plate 14 and provide a firm support for each of the members 16, so that any quantity of clothing or other articles may be hung upon these arms up to the point of their elastic strength, and when it is not desired to use any of the arms they may be collapsed or swung to the downward and vertical position, out of the way, by simply pulling them out-

wardly and away from the bracket until the angular portions 16^a register with the openings 15, which will allow the members 16 to have a hinging or swinging motion and to have their main body portions assume the perpendicular position, as shown in Fig. 2.

In order that the invention might be understood, the details of the preferred embodiment have been illustrated in the drawings and specifically described, but it is not desired to be limited to the exact details shown, for it will be apparent that various modifications may be made without departing from the purpose or spirit of the invention.

I claim:

A clothes hanger, comprising a bracket 60 having a substantially horizontal plate portion provided with perforations spaced from its edge and a downwardly depressed trough extending from each perforation to the edge of the plate, and horizontally disposed hanger rods each having an end portion disposed in one of the troughs and extending through a corresponding perforation, the portion of the rod extending through the plate having two right angle 70 bends spaced apart a distance substantially equal to the length of the trough in which such rod is disposed, providing means for supporting said rod in vertical position in such trough.

In testimony whereof I have signed my name to this specification, in the presence of two subscribing witnesses, on this 10th day of February, A. D. 1914.

PETER S. MEISTER.
